[57] CLAIM

The ornamental design for a working bowl for processing food with an attachable gear unit, as shown an described.

DESCRIPTION

FIG. 1 is a perspective view of the appliance, shown from the top right-hand corner, whereby a working tool is arranged in the working bowl and a lid detachable from the outside is arranged at the bottom thereof;

FIG. 2 is a front view of the appliance of FIG. 1;

FIG. 3 is a rear view of the appliance of FIG. 2;

FIG. 4 is a top plan view of the appliance of FIG. 3;

FIG. 5 is a view of the appliance of FIG. 2, shown from the right-hand side;

FIG. 6 is a view of the appliance of FIG. 2, shown from the left-hand side;

FIG. 7 is a bottom view of the appliance of FIG. 6;

FIG. 8 is a perspective view thereof, and the broken line showing a mixer is for illustrative purposes only and forms no part of the claimed design; and,

FIG. 9 is a perspective view of the working bowl shown separately for ease of illustration with the lid in an alternate position.
